DESIGN FOR AN IRONING MACHINE CABINET

Robert S. Condon, Rochester, N. Y.

Application December 17, 1936, Serial No. 66,601

Term of patent 14 years

To all whom it may concern:

Be it known that I, Robert S. Condon, a citizen of the United States, residing at Rochester, in the county of Monroe and the State of New York, have invented a new, original, and ornamental Design for an Ironing Machine Cabinet, as shown in the accompanying drawing, forming part of this specification.

In the drawing:

Fig. 1 is a front elevational view of an ironing machine cabinet in closed position, showing my new design.

Fig. 2 is an end elevational view thereof, in closed position.

Fig. 3 is a rear elevational view thereof with the hinged cover closed, and

Fig. 4 is an end elevational view thereof with the hinged cover in open position.

I claim:

The ornamental design for an ironing machine cabinet substantially as shown and described.

ROBERT S. CONDON.
